(57) **CLAIM**

The ornamental design for a service robot, as shown and described.

DESCRIPTION

FIG. 1 is a front, top, right-side perspective view of the service robot;

FIG. 2 is a front elevational view thereof;

FIG. 3 is a top plan view thereof;

FIG. 4 is a right-side elevational view thereof, the left-side elevational view (not provided) being a mirror image thereof;

FIG. 5 is a rear elevational view thereof; and,

FIG. 6 is a bottom plan view thereof.

The broken lines in the drawings depict unclaimed environmental subject matter.
